[57] CLAIM

The ornamental design for a combined towel warmer and fabric dryer, substantially as shown and described.

DESCRIPTION

FIG. 1 is a front perspective view of a combined towel warmer and fabric dryer, showing our new design;

FIG. 2 is a rear perspective view thereof;

FIG. 3 is a plan view of two sides thereof;

FIG. 4 is an elevational view of one of the three sides thereof;

FIG. 5 is an elevational view of another of the three sides thereof;

FIG. 6 is an elevational view of the third side thereof;

FIG. 7 is a front elevational view thereof;

FIG. 8 is a rear elevational view thereof.
